UNITED STATES PATENT OFFICE.

GEORGE P. WIGGINTON, OF KALAMAZOO, MICHIGAN.

TEMPORARY BINDER OR LOOSE-SHEET HOLDER.

1,136,573.

Specification of Letters Patent. Patented Apr. 20, 1915.

Application filed June 15, 1914. Serial No. 845,170.

To all whom it may concern:

Be it known that I, GEORGE P. WIGGINTON, a citizen of the United States, residing at Kalamazoo, Michigan, have invented certain new and useful Improvements in Temporary Binders or Loose-Sheet Holders, of which the following is a specification.

This invention relates to improvements in temporary binders or loose sheet holders.

10 The main objects of this invention are: First, to provide an improved temporary binder which is capable of very rapid manipulation to permit the insertion or removal of loose leaves. Second, to provide a temporary binder or loose sheet holder 15 of the flexible transverse cord type which may be readily embodied in small binders as well as in binders of considerable size. Third, to provide in a temporary binder or loose sheet holder an improved adjusting means. Fourth, to provide a temporary binder or 20 loose sheet holder of the class described which is very simple and economical in structure and at the same time strong and durable and secure.

Further objects, and objects relating to structural details, will definitely appear from the detailed description to follow.

25 I accomplish the objects of my invention by the devices and means described in the following specification.

The invention is clearly defined and pointed out in the claims.

30 A structure which is a preferred embodiment of my invention is clearly illustrated in the accompanying drawing forming a part of this specification, in which:

Figure I is a detail view of a structure embodying the features of my invention 35 with one of the covers open, the strands of one of the binding strips being spread apart to better show structural details, the sheets being illustrated in conventional form. Fig. II is an enlarged detail section 40 on a line corresponding to line 2—2 of Fig. I with the covers closed. Fig. III is an enlarged detail transverse section on a line corresponding to the broken line 3—3 of Fig. I. Fig. IV is a plan view of one of the binding strip retaining members 5. Fig. V is a detail transverse section corresponding to that of Fig. III of still another modification or embodiment of my invention. Fig. VI 45 is a plan view of a modified form of the binding strip retaining member 5.

In the drawing similar reference charac-

ters refer to similar parts throughout the several views, and the sectional views are taken looking in the direction of the little arrows at the ends of the section lines.

Referring to the drawing, the covers 1 of the structure illustrated are of flexible material and are secured to the rear edges of the binding or clamping members 2 to fold forwardly over the same when the 65 binder is closed. In the structure illustrated the covers are made of two thicknesses of material folded over and suitably glued to the binding members 2, which are preferably of metal.

70 The binding strips 3 are of suitable flexible material, and said strips are releasably secured to one of the binding members by means of the retaining members 5 which, in the structure illustrated in Figs. I-IV, are 75 I-shaped sheet metal stampings, the bar part of the retaining members being engaged in the loop of the binding strips on the outer end of the binding member.

70 In the embodiment illustrated in Figs. I-III the strands of the binding strips are arranged through pairs of slots 6 in the spring clutch or securing members 7 which are mounted on the other binding member by means of the rivets 8, the rivets being disposed through the inner ends of the securing members so that their outer ends are held 85 yieldingly toward the binding members. The rivets or studs 8 are preferably pivots for the securing members so that they may 90 be swung in a plane parallel to the plane of the side of the binding member on which they are mounted. This facilitates the assembling of the parts.

95 In the embodiment shown in Figs. I-III slots 6 are formed by slitting and turning the slit portions inwardly and downwardly to provide wedge-shaped clutch parts 9 which project into the slots of the binding member and engage the binding strips between the strands, clutching or clamping the strands against the edges of the slots. Any pull or strain which tends to separate the binding members draws the clutch or securing members tighter upon the binding strips 100 so that they are very firmly secured and, at the same time, they may be readily released by raising the free end of the securing members.

105 The ends of the strands are preferably connected after being passed through the slots 6 in the securing members by means of

the end clips 10. The ends of the clamping members are preferably turned up at 11 to provide finger holds. These upturned ends are adjacent to the ends of the binding members so that they may be conveniently grasped or engaged to release the same, an upward pull being all that is required. To tighten the binding strips it is only necessary to pull up on the same and press the binding member down. When the securing members are of spring material or spring actuated they automatically engage when the pull on the binding strips is discontinued.

15 In the embodiments illustrated the sheets or leaves 12 are provided with binding strip engaging slots 13. Perforations, may, however, be used if desired, the retaining members 5 being removed when it is desired to 20 thread perforated sheets upon the binding strips. I sometimes use binding strips having single strands.

25 In the embodiment shown in Fig. V the securing member 7' is provided with a pair of stud-like clutch members 8', the slots 6 of the embodiment shown in Figs. I, II and III being omitted.

30 The retaining member 20 shown in Fig. VI is a modification of the retaining member 5 shown in Fig. IV. The releasing member 20 is slotted at 21 to receive the binding strip strands and is not as readily detachable as the form shown in Fig. IV.

35 My improvements are well adapted for embodiment in small, light binders and are highly desirable where such binders are required. They are however, very desirable when embodied in binders of considerable size. The binders are simple and economical 40 to produce and hold the sheets very securely and are capable of very rapid manipulation.

45 I have not attempted to illustrate all the embodiments or modifications of my improvements which I contemplate as I believe the disclosure made will enable those skilled in the art to which my invention relates to embody or adapt the same as may be desired. I desire, however, to be understood as claiming my improvements specifically 50 in the form illustrated as well as broadly within the scope of the appended claims.

Having thus described my invention, what I claim as new and desire to secure by Letters Patent, is:

60 1. In a temporary binder, the combination of binding members having slots therein, covers connected to the rear edges of said binding members to fold forwardly over the same, binding strips folded to provide double strands arranged through the slots in said binding members, I-shaped retaining members removably engaged in the loops of said binding strips on the outer side of one of said binding members, and securing

members for said binding strips mounted on the outer side of the other binding member.

2. In a temporary binder, the combination of binding members having openings therein, binding strips folded to provide double strands arranged through the openings in said binding members, retaining members engaged in the loops of said binding strips on the outer side of one of said binding members, and spring clutch members having parts adapted to project into the binding member openings and engage the binding strips between the strands thereof, the ends of the strands of the binding strips being secured together, said retaining members being removable to release the binding strips.

3. In a temporary binder, the combination of binding members having openings therein, binding strips folded to provide double strands arranged through the openings in said binding members, removable retaining members engaged in the loop of said binding strips on the outer side of one of said binding members, and spring securing members having pairs of openings therein through which the strands of said binding strips are passed, the ends of the strands being secured together.

4. In a temporary binder, the combination of binding members having openings therein, binding strips folded to provide double strands arranged through the openings in said binding members, retaining members engaged in the loop of said binding strips on the outer side of one of said binding members, and spring securing members having pairs of openings therein through which the strands of said binding strips are passed.

5. In a temporary binder, the combination of binding members, binding strips having double strands connected to one of said binding members the other having slots through which said binding strips are arranged, and securing members mounted on said slotted binding member, said securing members having pairs of slots therein through which the strands of the binding strips are disposed and members between the pairs of slots adapted to project into the binding member slots and engage the binding strips between the strands thereof.

6. In a temporary binder, the combination of binding members, binding strips having double strands connected to one of said binding members the other having openings through which said binding strips are arranged, and spring securing members mounted on said binding member having the openings therein and having members adapted to project into the openings and engage the binding strips between the strands thereof.

7. A temporary binder comprising a bind

- ing member having openings therein, binding strips having double strands arranged through the openings in said binding member, and spring securing members mounted 5 on the outer side of said binding member with free ends disposed outwardly, said securing members having pairs of openings therein through which the strands of the binding strips are disposed and clamping 10 members between the pairs of openings adapted to project into the binding member openings and engage the binding strips between the strands thereof. 15 8. In a temporary binder, the combination of binding members, binding strips connected to one of said binding members the other having openings through which said binding strips are arranged, and spring securing members mounted on said binding member 20 having the openings therein to press normally toward the same and provided with parts adapted to project into the openings and engage the binding strips passing therethrough. 25 9. In a temporary binder, the combination of binding members, binding strips connected to one of said binding members the other having openings through which said binding strips are arranged, and securing members 30 mounted on said binding member having the said openings therein and having clamping members adapted to project into the openings of said binding member and engage the binding strips. 35 10. In a temporary binder, the combination of binding members, binding strips connected to one of said binding members the other member having openings therein through which said binding strips are arranged, and 40 spring clutch members mounted on said slotted binding member and held yieldingly toward the binding member on which they are mounted under spring tension to clutch the binding strips as they pass through the 45 openings, the binding strips being disposed relative to the clutch members so as to be disengaged by a pull on the free ends of the binding strips. 50 11. A temporary binder comprising a binding member having a slot therein, a binding strip having double strands arranged through said slot, and a spring securing member mounted on the outer side of said binding member, said securing member having a pair of slots therein through 55 which the strands of the binding strip are disposed, the slots being formed by slitting and turning the slotted portions inwardly, the inturned portions constituting a clamping wedge adapted to project into the binding member slot and engage the binding strips between the strands thereof. 60 12. A temporary binder comprising a binding member having an opening therein, a binding strip having double strands ar- 65 ranged through said opening, and a spring securing member mounted on said binding member and having a pair of openings therein through which said strands are passed, said securing member being tensioned to 70 press toward the binding member and being provided with a part engaging between the strands coacting with the edges of the binding member openings to clutch the binding strip. 75 13. A temporary binder comprising a binding member having an opening therein, a binding strip having double strands arranged through said opening, and a spring securing member mounted on said binding member and having a pair of openings therein through which said strands are passed, said securing member being tensioned to 80 press toward the binding member and coacting with the edges of the binding member opening to clutch the binding strip. 85 14. A temporary binder comprising a binding member having an opening therein, a binding strip arranged through said opening, and a spring securing member mounted 90 on said binding member to press normally toward the same and provided with a part projecting into the opening to engage the binding strip. 95 15. A temporary binder comprising a binding member having an opening therein, a binding strip arranged through said opening, a spring securing member mounted on said binding member to press normally toward the same and coacting with the edges 100 of the opening in said binding member to clutch the binding strip. 105 16. A temporary binder comprising a binding member having an opening therein, a binding strip having double strands arranged through the opening in said binding member, and a securing member for said binding strip adapted to project into the binding member opening and engage the binding strip between the strands thereof. 110 17. A temporary binder comprising a binding member having an opening therein, a binding strip arranged through said opening, and a spring securing member mounted 115 on said binding member to press normally toward the same and provided with an opening through which said binding strip is arranged and with a part normally projecting into the opening of said binding member to engage the binding strip. 120 18. A temporary binder comprising a binding member having an opening therein, a binding strip arranged through said opening, and a securing member having an opening to receive said binding strip and provided with a part projecting into the opening of said binding member to engage said binding strip. 125 19. A temporary binder comprising a binding member having an opening therein, 130

a binding strip arranged through said opening, and a securing member held normally toward the binding strip under spring tension to engage the binding strip and coacting with the edges of the opening of the binding member to constitute a clutch for the binding strip.

In witness whereof I have hereunto set my hand and seal in the presence of two witnesses.
